H. J. HARTIG.
CYLINDER BORING DEVICE.
APPLICATION FILED FEB. 4, 1920.

1,404,203.

Patented Jan. 24, 1922.

UNITED STATES PATENT OFFICE.

HENRY J. HARTIG, OF BROOKLYN, NEW YORK.

CYLINDER-BORING DEVICE.

1,404,203.

Specification of Letters Patent. Patented Jan. 24, 1922.

Application filed February 4, 1920. Serial No. 356,226.

To all whom it may concern:

Be it known that I, HENRY J. HARTIG, a citizen of the United States, and a resident of the borough of Brooklyn, county of 5 Kings, city and State of New York, have invented a new and useful Improvement in Cylinder-Boring Devices, of which the following is a full, clear, and exact description.

My invention relates to improvements in 10 devices for boring out cylinders, and is especially adapted for boring out the cylinders of engines, although the device can be used for re-boring any cylinder if desired. It is well known that it is rather frequently necessary to re-bore the cylinder of internal combustion engines, and it is also often desirable to re-bore or bore other cylinders, and the object of my invention is to produce a strong, 15 simple and inexpensive device by which such work can be easily and quickly accomplished. My invention is further intended to produce a device in which a flat body or cutter-bar is held in a simple form of packing and guide, the latter being expandable at one end, and 20 cylindrical in shape, so that it can be made to accurately fit a cylinder, and at the same time it will hold the body or cutter-bar so that it will not wobble or chatter, and will be held in position to bore accurately. In 25 carrying out my invention I use a cylindrical form of two-part packing and guide which fits snugly in the cylinder to be bored, and which is of softer material than the cylinder operated on, so that there will be no danger 30 of scratching the cylinder. The material may be hard wood, hard rubber, fibre, or any good firm material which is not too hard. The packing carries the body or cutter-bar which projects from the outer end thereof, 35 so that it can be gripped by the wrench or other means of operating it, and the cutting edges of the body or cutter-bar project slightly from opposite sides of the packing and guide so as to properly engage the cylinder 40 wall. The expandable end of the packing and guide can be adjusted by a very simple screw attachment, and the whole structure is simple, cheap, and strong, and therefore well adapted to quickly and accurately bore 45 cylinders.

Reference is to be had to the accompanying drawings forming a part of this specification, in which similar reference characters indicate corresponding parts in all the 50 views.

Figure 1 is a side elevation of the tool or device embodying my invention.

Figure 2 is a longitudinal section on the line 2—2 of Figure 1.

Figure 3 is a cross section of the device on 60 the line 3—3 of Figure 1.

Figure 4 is an inside end view of the device, and

Figures 5 and 6 are an elevation and cross section, respectively, of a slight modification 65 of the invention.

In carrying out my invention I use a packing and guide formed of two nearly semi-cylindrical parts 10 which are adapted to clamp the body or cutter-bar 15 between 70 them, and when the cutter-bar is in place the packing and guide is cylindrical, and its lower or expandable end presently referred to, must form an accurate circle in cross section. The packing is hollow at its inner 75 end as shown at 11, and is slit longitudinally at intervals as shown at 12, thus forming a series of segments 13 which can be expanded slightly, and which the natural spring of the material permits. The inner sides of the 80 segments 13 are beveled as shown at 14 in Figure 2, for the purpose of providing for expansion, as presently described. The body or cutter-bar 15 which clamps between the 85 sections 10 of the packing projects from the outer end as shown at 15^a, so that a tool, as a wrench or the like, can be applied to it in order to turn the device, and the body or cutter-bar projects very slightly from opposite sides, and is beveled as shown in Figure 90 3, to form two cutting edges 16 which are diagonally opposite each other, and which projects slightly from the packing, this projection being sufficient to re-bore the cylinder to the desired extent. The outer end of the 95 cutter-bar is also preferably pierced as shown at 17, to facilitate the attachment of certain kinds of handles or shanks for turning, and the two parts 10 and the cutter-bar 15, are clamped together by cross-bolts 18, 100 the heads 19 and nuts 20 of which are countersunk in the member 10.

At the inner hollow end of the packing 10 is a slide block 21 which fits snugly in the holder, and the outer portion of which is 105 beveled as shown at 22 to fit the beveled parts 14 of the segments 13. A bolt 23 extends longitudinally through the block 21 and screws into the inner end of the body or cutter-bar 15.

It will be seen, therefore, that by screwing in the bolt 23, the block 21 and its beveled part 22 will be drawn inward, and the part 22 will have a wedge action upon the bevel parts 14 and the segments 13, thus expanding them, and this expansion can be regulated, obviously, so that the diameter of the expanded part will fit the cylinder nicely. The tool is now ready for use, and can be 10 inserted in the cylinder and twisted around in the customary manner so that the cutting edges 16 of the body or cutter-bar will cut the walls of the cylinder to the desired extent, and as the tool is accurately guided by 15 its packing, the walls will be cut with sufficient accuracy.

In practice I have generally used the body or cutter-bar 15 with the cutting edges 16 formed directly thereon as described, but obviously the body or cutter-bar can be provided with expandible bits if desired, so that after a cylinder has been re-bored once, it can be easily bored repeatedly with the same tool by expanding the cutting bits. 25 This expandible cutter can obviously be made in very many well-known ways, and in Figures 5 and 6 I have shown one way of expanding the cutters. As here illustrated, the body or cutter-bar 15 and its 30 packing and guide are used as described, but the cutter-bar has the holes 24 through which the clamping bolts 18 extend, elongated so as to provide for longitudinal movement, and in the side edges of the cutter-bar are bits 25 which have their outer ends beveled as shown at 26, and wedging against corresponding walls 27 of the cutter-bar, the bits being held in recesses in the edges of the cutter-bar as shown. The bits 35 25 can be held by transverse bolts 28, suitably countersunk in the members 10, and to provide for lateral movement the holes 29 through which the bolts 28 extend, are elongated laterally. With this construction it 40 will be seen that when the block 21 is forced inward to expand the end of the packing, the body or cutter-bar 15 will also be drawn towards the block 21, both parts moving slightly, and the walls 27 wedging on the 45 walls 26 of the bits 25 will force the bits outward. These are held against longitudi-

nal movement by the cross-abutments 30. The details of this expandible arrangement are not claimed, and the structure shown in Figures 5 and 6 is simply to illustrate 45 the fact that the cutter may be expandible if desired, and as stated, other forms of expanding the cutter can be used without affecting the invention.

It will be observed that this invention is 60 different from most expandible reamers and tools of like nature, in that the packing for the cutting tool is expandible and adapted to fit snugly in the hole which is being re-bored, so as to prevent the tool from wobbling, while the tool itself is set to cut the bore to the desired diameter. 65

I claim:—

1. A cylinder boring tool comprising a substantially flat body, cutters mounted to 70 project beyond the side edges thereof, a substantially semi-cylindrical packing of softer material than the body mounted on each side face of and projecting beyond the forward end of the body and having a diameter substantially that of the cutters, and means carried in said projecting ends to expand the packings. 75

2. A cylinder boring tool comprising a substantially flat body having cutters projecting beyond the side edges thereof, a substantially semi-cylindrical packing of softer material than the body mounted on each side face of and projecting beyond the forward ends of the body and having a diameter substantially that of the cutters, said projecting ends being slotted longitudinally to render them easily expandible, and a wedge shaped member fitting in the said projecting ends of the packing and having means 80 for adjustment therein. 85

3. A device according to claim 2 characterized by the further fact that the wedge shaped member for adjusting the slotted end portions of the packing is operated by 90 a screw extending through said member and into the body or cutter-bar. 95

HENRY J. HARTIG.
